DESIGN FOR A CLOCK CASE

Irwin W. Kokins, Ashland, Mass., assignor to
Warren Telechron Company, a corporation of
Maine

Application September 12, 1935, Serial No. 58,522

Term of patent 14 years

To all whom it may concern:

Be it known that I, Irwin W. Kokins, a citizen of the United States, residing at Ashland, county of Middlesex, State of Massachusetts, have invented a new, original, and ornamental Design for a Clock Case, of which the following is a specification, reference being had to the accompanying drawing, forming a part thereof. The figure

is a front perspective view of a clock case showing my new design.

I claim:

The ornamental design for a clock case as shown.

In witness whereof, I have hereunto set my hand this 6th day of September, 1935.

IRWIN W. KOKINS.
